SAFETY RAZOR

John T. Scully, New York, N. Y.

Application January 29, 1945, Serial No. 575,002

3 Claims. (Cl. 30—72)

1

The present invention relates to safety razors generally and more particularly to the type wherein a thin, replaceable or detachable, flexible razor blade is flexed and clamped between cap and guard members having cooperative blade-flexing faces shaped to flex the blade accurately, the cap and guard members being relatively movable towards or away from each other by manipulation of a threaded handle; such razors being commonly known as of the "Gillette type."

Among the objects of the invention is the provision of a safety razor of simple construction, and of easy and economical manufacture; the provision of a safety razor, embodying a replaceable, facedly reversible, flexible razor blade, having improved means for positioning the blade and guiding it as it is being flexed between clamping members, for improved parallelism of the shaving edges with the axis of the razor head and improved equalization of shaving edge projection on opposite sides thereof; the provision of a safety razor having such improved blade guiding means and a guard member facedly reversible to the cap member for providing variations of exposure of the shaving edges of the blade to the guard at a given degree of flexure of the blade and, especially, to provide a relatively high or relatively low exposure of the shaving edges to the guard, according to which of the guard faces faces the blade, at the maximum degree of blade flexure or when the blade is most tightly clamped.

Other objects will hereinafter be apparent from the description taken in connection with the accompanying drawing.

The invention resides in the combinations and arrangements of parts, the cooperative action of parts, and the construction of individual parts hereinafter described and claimed.

Referring to the drawing forming a part of the specification and in which similar reference characters refer to similar parts throughout the several views:

Fig. 1 is a side perspective view of the component parts of the razor in disassembly, a portion of the handle being shown in section. Fig. 2 is an end view of the guard member. Fig. 3 is an end view, partly in section, of the cap member. Fig. 4 is an end view, partly in section, of the razor head showing the razor blade clamped in operative shaving position between the cap and one blade-flexing face of the guard member. Fig. 5 is an end view showing the blade clamped substantially as tightly as in Fig. 4 between the cap and the other blade-flexing face of the guard member. Fig. 6 is an end view, with parts shown in section, showing the relative positions of parts

2

just prior to flexing and clamping the blade as in Fig. 4. Fig. 7 is a side elevation of the razor head with the parts in position as in Fig. 4. Fig. 8 is a plan view of a typical double edge flexible razor blade. Fig. 9 is an end view showing a modification of guard member. Fig. 10 is a top elevation of a modification of a part of the guard member. Fig. 11 is a plan face view of a further modification of guard member. Fig. 12 is a sectional view taken on line 12—12 of Fig. 11 with the part turned ninety degrees. Fig. 13 is a side elevation of a modification of the guard member shown in Figs. 11 and 12.

Referring more particularly to the drawing:

The embodiment of the invention illustrated in Figs. 1 to 8 inclusive comprises a cap member 20, double edge perforated flexible razor blade 21, guard member 22 and handle 23. Cap member 20 has projecting from its concave or blade-flexing face central externally threaded post 24 of sufficient length to extend through the blade and guard member into the threaded end of the handle, and on opposite sides of, and spaced from, the central post are rigid aligning and positioning studs 25 and 26. Blade 21 is of the usual and well known construction, being perforated centrally in the form of slot having enlarged portions 27, 28 and 29 to receive cap post and cap studs 24, 25 and 26, and is of normally straight thin body longitudinally, as indicated by 30, and is provided with the usual oppositely disposed, sharpened, longitudinal edges providing the shaving edges 31 and 32. Guard member 22 is provided with three aligned longitudinally spaced cylindrical holes 33, 34 and 35 extending from one blade-flexing face of the member to the other to receive cap post and studs 24, 25 and 26 and, preferably, is substantially the same length as the cap member 20 with flat end faces 36. The parts are assembled in the usual manner: threaded cap post 24 being engaged by internal threads 37 of the handle, members 20 and 22 being forced towards each other, relatively, by the turning of the handle, causing blade 21 to be transversely flexed and clamped by the cooperative action of concave blade-flexing face 38 of the cap, more particularly the longitudinal edges of the face, and one of the blade-flexing faces 39 or 40 of the guard member.

Referring more particularly to reversible guard member 22, the convex blade-flexing faces 39 and 40 are transversely curved on the same radius and have a curvature substantially complementary to blade-flexing face 38 of the cap. Projecting laterally outwardly of faces 39 and 40, on opposite longitudinal sides thereof and equidis-

stant laterally therefrom, are parallel, longitudinal skin guards 41 and 42 which may be formed in the guard member in any suitable manner known in the art and of any suitable material or materials; as shown herein, the guard member comprises a laminated assembly of a rigid, rectangular, flat sheet 43 fixedly secured between plano-convex rigid parts 44 and 45, parts 43, 44 and 45 being suitably fastened together by riveting, or soldering, or welding, as may be desired, and, as shown herein, by soldering. The projecting and longitudinally extending ends of skin guards 41 and 42 are symmetrically rounded on opposite faces of sheet 43 and on opposite sides of the guard member as indicated at 46, 47 and at 48, 49, the shape and length of curvature of the rounding being the same on both faces and at both sides of the sheet and being so shaped and related to the curve of blade-flexing faces 38, 39 and 40 as to provide a shaving angle or angles according to the best practice in the art or commerce. Important features in the reversible guard member 22 are that either blade-flexing face thereof is cooperative with the cap member for flexing and clamping the razor blade with the shaving edges thereof in operative shaving position to the skin guards and that one blade-flexing face, 39, is lower relatively to the skin guards than the opposite blade-flexing face 40, whereby, when the blade is clamped tightly between faces 38 and 39, the shaving edges of the blade will be exposed relatively to the skin guards preferably substantially as high as in the best commercial practice employed in the improved razors of the Gillette type when the parts thereof are similarly tightly clamped and the blade flexed substantially to the same degree; and, further, whereby, when the blade is clamped tightly to the same degree between faces 38 and 40, the shaving edges of the blade will be exposed higher relatively to the skin guards; in both cases, however, neither face 39 nor face 40 is too high relatively and to the skin guards for operative shaving in the usual safe manner and, preferably, face 40, the higher face, is low enough to the skin guards to permit operative shaving in a safe manner with less than full flexure of blade and, consequently, with a still relatively higher exposure of shaving edges to skin guards. The difference in height, relative to face widths and to skin guards, of faces 39 and 40 may be any suitable distance within the limits of operative shaving and is such a distance, preferably, whereby, when the blade is clamped to the same degree of tightness between cap and face 39 or cap and face 40, the difference in height of shaving edge exposure to the respective skin guards is not greater than twice the height of the lower shaving edge exposure and, preferably, does not exceed one-one hundredths of an inch, and, more preferably, does not exceed .004 of an inch in some instances, the guard member may be made with a relative difference in face heights which will, when the blade is clamped to the same degree of tightness between the cap and face 39 or between the cap and face 40, effect a difference in height of shaving edge exposure to the respective skin guards of not more than .002 of an inch, or substantially .002 of an inch. Since guard member 22 is shown with convex faces 39 and 40 curved on the same radius and having the same widths (and also the same width as face 38 of the cap 20), it will be clear, upon reference to Fig. 2, that for purposes of illustration the referred to relative difference in face heights will be understood by considering the line A—A' a plane through the

guard member at the edges of its blade-flexing face 39 and paralleling a plane axially through the skin guards represented by the line B—B', and by considering the line C—C' a plane through the guard member at the edges of its blade-flexing face 40 and paralleling A—A' and B—B'. It will readily be seen that the distance between A—A' and B—B' is less than the distance between B—B' and C—C' and that, consequently, blade-flexing face 39 is lower relatively to skin guards 41 and 42 than is blade-flexing face 40 (it having been observed that guard faces 46, 47, 48 and 49 are symmetrically related to axial plane B—B').

Cap studs 25 and 26 are provided, for a portion of their lengths, with lateral parallel sides forming opposite lateral sides of the cylindrical portions 50, 50, the inner ends of which are spaced from a plane contiguous with the blade-flexing edges of the cap member by a suitably short distance which, preferably, is a distance between .004 of an inch and .003 of an inch. The portions 50, 50 constitute blade positioning or locating means for positioning the blade with its shaving edges substantially equally exposed laterally to and extending substantially parallel with the blade-flexing edges of the cap member before the blade is flexed into operative shaving position, and constitute, together with the holes 34 and 35 in the guard member, cap and guard aligning means or guard-guiding means, cylindrical portions 50, 50 having a close, but practicable, sliding fit in holes 34 and 35 and being of suitable length for initially positioning the cap and guard members and the blade and for guiding the movements of the cap and guard members relatively towards, or away from, each other. The inner ends of the studs 25 and 26 extending from cylindrical portions 50, 50 to the inner or concave face of the cap member have laterally inclined sides converging in the direction of the concave face of the cap and forming opposite lateral sides of frusto-conical portions 51, 51 of the studs whose outer and free ends 52, 52 have the usual dome shape for easy entrance into blade and guard holes. Inclined portions 51, 51 have a definite degree of inclination or rate of taper, for their lengths, definitely related to the degree of flexure of the blade that the blade-flexing faces of the cap and guard members will effect, and constitute blade-guiding means for guiding the arcing of the blade during all degrees of transverse flexing to maintain the shaving edges of the blade substantially equally exposed laterally to and extending substantially parallel with the blade-flexing edges of the cap member and the skin guards of the guard member. The studs may be cast integral on the cap or made of a different and suitable material and welded or soldered in holes and in accurate alignment in the cap as shown in Fig. 3, the studs being provided with cylindrical end portions 53 for the purpose; in some instances, the holes in the cap may be internally threaded and portions 53 externally threaded for cooperative fastening engagement. Blade locating or positioning portions 50, 50 of the studs have a width between their respective opposite lateral sides only slightly less than holes 28 and 29 of the blade in order that the blade may be accurately, if not so quickly, positioned thereon initially, and center post 24 of the cap member has a diameter smaller enough than hole 27 of the blade to prevent the hole walls of the blade from catching on the threads of the post before or during flexure of the blade. In Fig. 4, the parts are shown tightly drawn together with

the cap and guard members held in proper alignment by the cooperative action of stud portions 50, 50 and guard hole walls 54, 54, and with the blade tightly clamped between the blade-flexing face of the cap member and the low blade-flexing face of the guard member and providing the low exposure of blade shaving edges to skin guards as indicated by the distance of a plane contiguous with the shaving edges of the blade and represented by the line D—D' from the parallel plane, represented by the line B—B', through the axis of the skin guards; as will be observed, the blade has been transversely flexed and arched upwardly or in the direction of the cap member by the turning of the handle and the forcing of the parts together, and with the lateral walls of the blade adjacent the holes 28, 29 thereof, more particularly, due to the direction of blade arcing, the portions of the lateral walls of the blade which are on the shorter radii, as indicated at 55, having cooperated with frusto-conical portions 51, 51 of the cap studs to position the blade with the shaving edges thereof substantially equally exposed laterally to the respective skin guards.

In Fig. 5, the parts are shown drawn together to the same degree of tightness as shown in Fig. 4, but with the guard member reversibly faced so that the blade is clamped between the cap member and the high blade-flexing face of the guard member providing the high exposure of blade shaving edges to skin guards as indicated by the distance of a plane contiguous with the shaving edges of the blade, and represented by the line E—E', from the parallel plane, represented by the line B—B', through the axis of the skin guards. In Fig. 6, the relationship of parts is shown in their position just before the blade will go under tension and where the slightest tightening of the handle will cause the commencement of blade flexing: one face of the blade is touching the blade-flexing edges of the cap member, and the opposite face of the blade is tangentially touching the blade-flexing face of the guard member, in this instance low face 39, substantially centrally along said face; and with the cap and guard aligning and blade positioning or locating cylindrical portions of the cap studs well seated in the guard member and providing the proper alignment of the parts. With the parts in this position, the cylindrical portions of the cap studs extend almost clear through the blade holes, the inner ends 56 of said portions being in position in the holes of the blade at a depth between one-half to two-thirds of the blade; the frusto-conical blade guiding portions of the cap studs extend substantially the remaining distance into the blade holes; and since the usual blade may be either "regular" and .006 thick or "thin" and .004 of an inch thick, the blade 21 shown here may, for purposes of this illustration, be considered as of .006 of an inch thickness, and the depth, to give a concrete example, from the cap contacting face, to which ends 56 and the conical portions of the cap studs extend into the holes of this blade is, as shown, but not by way of limitation, approximately midway between .003 and .004 of an inch in order that a thinner blade, for example a blade .004 thick, may be properly positioned and guided. In the position shown, the blade is substantially prevented from lateral movement by the lateral sides of the portions of the cylindrical portions of the cap studs which are in the blade holes, the conical or guiding portions being substantially V-spaced, as indicated at 57, 57, from the rectangular or

vertical wall faces of the blade holes. As the cap and guard members are forced relatively towards each other by the turning of the handle and the blade is being flexed, the blade holes become smaller laterally so that the wall portions of the blade opposite the lower portions or bottoms of the holes will be guided, compensatory to reduction in hole size, by the inclined or conical portions of the cap studs whereby, when the blade is clamped for operative shaving, the shaving edges of the blade will be substantially equally exposed laterally to the respective skin guards, as shown in Figs. 4 and 5 and previously described.

In the modification shown in Fig. 9, the reversible guard member 22a, of similar laminated structure, has oppositely disposed flat blade-flexing faces 39a and 40a of equal width and narrower than the cap member which laterally overhangs the rounded fulcrum edges of the blade-flexing faces of the guard member. As shown in this modification, the parts are clamped to the same degree of tightness as the parts shown in Fig. 4, with the parts functioning in the same manner for positioning and guiding the blade for substantially equalized exposure laterally of the shaving edges to the skin guards, and to provide the same high or low exposures of the shaving edges to the skin guards as previously described. The distance between planes D—D' and B—B' is the same as described in connection with Fig. 4, and blade-flexing face 40a cooperates with the cap to provide the high exposure of blade shaving edges described in connection with Fig. 5; in the construction shown in Fig. 9, however, as will be observed, because of the narrower blade-flexing faces of the guard member, the heights of the blade-flexing faces thereof are respectively greater than in the construction shown previously (Fig. 2), the planes F—F' and G—G' being respectively higher relatively to the plane B—B' than the planes A—A' and C—C', but the relative difference in heights of faces 39a and 40a and the actual heights of blade shaving edge exposure to the respective skin guards, as indicated by the planes D—D' and B—B', are the same as in the previously described construction. Either of the described guard members may have lather passing longitudinal slots on opposite lateral sides, and in Fig. 10 is shown a modification of the rigid rectangular sheet portion 43a, of the laminated assembly of guard member shown in Fig. 9, having lather passing slots 58 and 59 extending longitudinally on opposite sides thereof and behind the skin guard bars 41a and 42a, the slots being laterally disposed to the blade-flexing faces of the guard member with the longitudinal side walls of the latter, at the rear of the slots, vertically flush with the inner sides of the slots.

In the modification of the part shown in Figs. 11 and 12, guard member 22b is of one piece construction and is provided with oppositely disposed lather passing slots 53a and 59a respectively spacing skin guard bars 41b and 42b from the blade supporting head; the cap central post receiving hole 33a is countersunk, as indicated at 33b, in both blade-flexing faces 39a and 40a to receive the threaded end of the handle; in other respects, guard member 22b is the same as the previously described guard member 22a.

In the further modification of the guard member shown in Fig. 13, guard member 22c is provided with oppositely disposed skin guard bars 41c, opposite ends of which, at the ends of the lather passing slots, provide blade corner skin

guards in the form of shoulder ends 60, 61 which are relatively higher than the intermediate portions of the skin guard bars at their tops and bottoms, but substantially flush with the front and skin engaging faces of the rounded guard teeth 62 alternately spaced in the bars by grooves 63 extending rearwardly to the outer sides of the lather passing slots. Shoulder ends 60, 61 are low enough relatively to the respective blade-flexing faces of the guard member so as not to interfere with a tight clamping of the blade, especially a thin blade .004 of an inch in thickness, and so as not to distort the blade corners which will be, preferably, spaced, when the blade is tightly clamped, a suitably short distance above the shoulders for the purpose of avoiding contact therewith and for enabling the shoulders to more closely guard the blade edge corners than the skin guard bar portions between the shoulders guard the shaving edges of the blade between the blade edge corners. Shoulders 60, 61 may, if desired, be symmetrically high with respect to the blade-flexing faces of the guard member whereby both blade-flexing faces will have the same height with respect to the corresponding adjacent shoulder ends of the skin guards and whereby shoulder ends 60 and 61 adjacent the high face 40a will be relatively higher to guard teeth 62 than the shoulder ends correspondingly adjacent the low face of the guard member will be to teeth 62. As shown herein, shoulder ends 60 and 61 are symmetrically high with respect to teeth 62 and, consequently, the shoulder ends correspondingly adjacent face 40a are lower relatively thereto than the shoulder ends correspondingly adjacent the low face are relatively to the low face. In other respects, guard member 22c is the same as guard member 22b.

While I have illustrated and described the invention in the preferred form, I wish it to be understood that the invention is not limited to the precise details shown and described and that variations and modifications may be made within the spirit and scope of the appended claims.

Having thus described my invention what I claim as new and desire to secure by Letters Patent is:

1. A safety razor including, in combination, relatively movable cap and guard members having blade-clamping faces cooperative for transversely flexing and clamping a flexible razor blade, the cap member having a hollow blade-clamping face, the guard member being facedly reversible and having two oppositely disposed blade-clamping faces either of which is cooperative with the cap member for transversely flexing the blade, skin guards forming opposite longitudinal side edges of the guard, one of said blade-clamping faces of the guard member being higher at its sides above the skin guards than the other, rigid blade-positioning projections extending downwardly from the cap member to engage the guard member for guiding said members relatively towards each other, said projections having slightly tapered upper side portions tapering in the direction of the cap member for guiding the blade as it is being flexed and centrally arched towards the cap member for positioning the blade relative to the guard member,

and a handle member for moving said cap and guard members relatively towards each other.

2. A safety razor including, in combination, relatively movable cap and guard members having blade-clamping faces cooperative for transversely flexing and clamping a flexible razor blade, the cap member having a hollow blade-clamping face, the guard member being facedly reversible and having two oppositely disposed blade-clamping faces either of which is cooperative with the cap member for transversely flexing the blade, skin guards forming opposite longitudinal side edges of the guard and having, at opposite ends, shoulders forming blade-corner skin guards disposed relatively higher to the blade-clamping faces of the guard member than the skin guard portions between said shoulders, one of said blade-clamping faces of the guard member being higher at its sides above the skin guards than the other, rigid blade-positioning projections extending downwardly from the cap member to engage the guard member for guiding said members relatively towards each other, said projections having slightly tapered upper side portions tapering in the direction of the cap member for guiding the blade as it is being flexed and centrally arched towards the cap member for positioning the blade relative to the guard member, and a handle member for moving said cap and guard members relatively towards each other.

3. A safety razor including, in combination, relatively movable cap and guard members having blade-clamping faces cooperative for transversely flexing and clamping a flexible razor blade, the cap member having a hollow blade-clamping face, rigid blade-positioning projections extending downwardly from the cap member and having guard-guiding side portions to engage the guard member for guiding said members relatively towards each other, said projections having slightly tapered upper side portions tapering in the direction of the cap member for guiding the blade as it is being flexed and centrally arched towards the cap member for positioning the blade relative to the guard member, said guard-guiding side portions of said projections being so adapted to the blade-clamping face of the cap member as to be disposed in the blade for initially positioning the blade when the latter is in a flat condition and in surface engagement with the blade-clamping faces of said members, and a handle member for moving said cap and guard members relatively towards each other.
